SASH HOLDING DEVICE

Archie A. Sawyer, Laramie, Wyo.

Application July 23, 1953, Serial No. 369,918

5 Claims. (Cl. 268—128)

This invention relates to a sash holding device, and has particular reference to a device for holding in adjusted vertical positions a window sash preferably operable by power means such as cables and pulleys for vertically adjusting the window.

An important object of the invention is to provide a novel simplified type of device operable in conjunction with a window sash, preferably of the plate glass type, for holding the sash in any vertically adjusted position and to permit it easily to be moved upwardly or downwardly as desired.

A further object is to provide such a device which is particularly intended for use with a cable operating means which, in itself, forms no part of the present invention, and wherein the device provides means for holding a sash in any adjusted position and permits the free upward movement of the sash while preventing downward movement thereof except through proper operation of the holding means.

A further object is to provide such a device wherein an operating arm, attached to the window in a novel manner, has its lower end inclined outwardly for engagement with a surface of the window casing to act as a brake to prevent downward movement of the window under its own weight from any adjusted position, but wherein the braking pressure on the arm is released by transmission of a pull thereon in a direction to move the sash downwardly, the sash being freely movable upwardly without any effective braking action.

A further object is to provide such a device wherein the braking arm extends downwardly and outwardly at a slight angle from the edge of the sash into engagement with a braking surface and is urged into braking engagement with such surface, and wherein the transmission of a pull through a cable or the like directly vertically downwardly on the arm releases its braking engagement with the sash to permit the window to be moved downwardly.

A further object is to provide such a device wherein certain operating parts may be omitted if the device is to be operated by cable means having its own holding means associated therewith, thus rendering the braking device of the present invention unnecessary in operation.

In the drawing I have shown one embodiment of the invention. In this showing:

Figure 1 is a horizontal sectional view through a window frame showing the invention applied, parts being broken away;

Figure 2 is a vertical section taken substantially on the line 2—2 of Figure 1;

Figure 3 is a detail horizontal sectional view on line 3—3 of Figure 2;

Figure 4 is a detail sectional view looking in the same direction as Figure 2 but showing the parts in section;

Figure 5 is an edge elevation of the holding device, and

Figure 6 is a detail side elevation showing a modified

2

use of the device without the employment of the braking means.

Referring to the drawing, and particularly Figures 1 and 2, the numeral 10 designates a window frame as a whole the particular form of which is unimportant in the present invention. The window frame accordingly need not be described in detail. It will be noted however that the frame is vertically recessed as at 11 for reception of the parts of the present invention described below. The recess 11 preferably is provided in the back wall thereof with a felt or similar layer 12 forming a friction surface engageable with a brake arm to be referred to.

The present invention has been illustrated in conjunction with plate glass windows, two of which have been shown in Figure 1 and indicated respectively by the numerals 13 and 14, the former of which may be the upper of a pair of window sashes and the latter of which is the lower sash. In the present installation, the face of the frame 10 adjacent the window and on opposite sides of the recess 11 is provided with a pair of clamping devices 15 attached to the window frame and supporting felt or similar strips 16 engageable with the remote faces of the sashes 13 and 14. Between these sashes is arranged another felt strip 17 supported with respect to the inner extremity of the groove 11 by one or more spacers 18 through which pass screws 19 for attaching the felt strip in position as shown in Figure 1. Accordingly, it will be apparent that the plate glass sashes operate between adjacent pairs of felt strips to provide leak proof joints.

A holding unit is employed in conjunction with each of the sashes, and each holding unit is indicated as a whole by the numeral 22. Each of these units comprises a casing shaped as shown in profile in Figure 2 and comprising side walls 23 which extend downwardly to form the side walls of an arm 24 which is inclined toward the left as shown in Figure 2 whereby its lower flattened end 25 is adapted to seat against the felt strip 12 in the bottom of the recess 11, as shown in Figure 2. The arm 24 is provided with inner and outer walls 26 and 27 (Figure 4) the former of which terminates at its upper end as at 28 to form an opening 29 in the wall 26 of the holding device.

The holding device is substantially enlarged horizontally at its upper end and receives a wheel 32 adapted to engage and roll over the felt strip 12 as shown in Figure 2. This wheel 32 is rotatably supported with respect to the holding device by means of a shaft 32' extending through the side walls 23.

To the right of the wheel 32, the housing of the holding device is horizontally extended as at 33 and receives a socket 34 (Figures 3 and 4) receiving a ball 35 having an opening 36 therethrough for a purpose to be described. The ball 35 carries a stem 37 riveted to a spring member 38 intermediate the ends thereof. This spring member is in the form of a leaf spring having diverging arms 39 terminating in ends 40 lying in a common plane and slidable beneath lips 41 carried by a channeled strip 42 embracing the edge of the associated sash as shown in Figure 3. The channel 42 may be retained in fixed position relative to the sash in any suitable manner, for example, by being cemented thereto. It will be apparent in Figure 4 that there is free play beyond the ends of the flat spring portions 40 whereby distortion of the spring incident to altering the angular position of the ball stem 37 permits free movement of the spring ends 40. This movement is also permitted through any irregularities in the cooperating parts of the device by which the stem 37 may be forced toward the edge of the sash to expand the spring ends for movement away from each other. At the same time, the spring forms positive means for connecting the ball 35 to the adjacent edge of the adjacent

50 To the right of the wheel 32, the housing of the holding device is horizontally extended as at 33 and receives a socket 34 (Figures 3 and 4) receiving a ball 35 having an opening 36 therethrough for a purpose to be described. The ball 35 carries a stem 37 riveted to a spring member 38 intermediate the ends thereof. This spring member is in the form of a leaf spring having diverging arms 39 terminating in ends 40 lying in a common plane and slidable beneath lips 41 carried by a channeled strip 42 embracing the edge of the associated sash as shown in Figure 3. The channel 42 may be retained in fixed position relative to the sash in any suitable manner, for example, by being cemented thereto. It will be apparent in Figure 4 that there is free play beyond the ends of the flat spring portions 40 whereby distortion of the spring incident to altering the angular position of the ball stem 37 permits free movement of the spring ends 40. This movement is also permitted through any irregularities in the cooperating parts of the device by which the stem 37 may be forced toward the edge of the sash to expand the spring ends for movement away from each other. At the same time, the spring forms positive means for connecting the ball 35 to the adjacent edge of the adjacent

sash, and the ball 35 in turn supports the body of the holding device 22.

To the arm 24 near the lower end thereof is secured a stem 44, welded or otherwise secured to the arm 24, and extending therefrom substantially perpendicular to the adjacent edge of the adjacent sash. The stem 44 extends relatively loosely into the open end of a sleeve 45, secured by welding or the like, to the outer face of the lower end portion of the channel 42. A compression spring 46 is arranged in the tube 45 and urges the lower end of the arm 24 into engagement with the felt strip 12.

The device as illustrated and described is intended to be operated by suitable mechanism of more or less conventional type such as a cable device running around pulleys, and since such device forms no part per se of the present invention it has been diagrammatically shown in Figure 2. Referring to such figure, the numeral 50 designates a cable as a whole having an end 51 connected at its upper end to the lower end of the arm 24 and extending downwardly around a pulley 52 shown in the present instance as having an operating crank 53. Beyond the pulley 52, the cable extends upwardly as at 54 and around an upper pulley 55, thence downwardly as at 56 for connection with the top wall 57 of the holding device 22. It will be noted that the end 51 of the cable is substantially vertical and when a pull is exerted thereon, the line of pull will be at a slight angle to the arm 24, to relieve braking pressure of this arm against the felt strip 12 as will become more apparent below.

If the device is to be used in conjunction with a power or similar operating means having its own holding means associated therewith, the body of the holding device 22, including the arm 24, together with the stem 44, tube 45 and spring 46 may be eliminated. In other words, the device as shown in Figure 6 may be employed, including only the spring 38, stem 37 and ball 35, attached to the securing clip 42. Under such conditions, a cable 60 may be attached to the ball 35 by being passed through the opening 36 therein. The spring 38 under such conditions provides a cushioned connection between the cable 60 and the associated sash, the spring 38 being capable of flexing and distortion to cushion any sudden forces applied to the window through the cable 60.

Operation

The holding device for each of the sashes will operate in a manner which will be clear from an examination of Figures 2 and 4, and accordingly, the operation need be described only as to one such holding device. The holding devices will be identical for the two sashes as stated and these sashes preferably but not necessarily are mounted in the manner shown in Figure 1, the sashes being of plate glass and operating within the felt strips 16 and 17 which form sealing means as well as guiding means for the sashes.

Assuming that the window is to be raised, the crank 53 may be rotated counterclockwise to pull down on the cable run 54 and exert an upward force on the cable end 56, which force will be transmitted to the body of the holding device 22. Inasmuch as the arm 24 is arranged at an acute angle to the strip 12, a direct upward force may be applied through the cable end 56 to elevate the sash, the brake surface 25 merely sliding over the felt strip 12. If desired, the sash may be directly manually raised by exerting an upward force thereon in the usual manner, and again the braking surface 25 will merely slide over the felt 12.

It will be apparent that the arm 24 has its surface 25 engaging the felt strip 12 and any tendency for the window sash to lower of its own weight, or under the influence of force applied directly thereto, will tend to swing the arm 24 toward the left as shown in Figure 2, the lower end of this arm thereupon acting as a brake to prevent downward movement of the window. This braking action is greatly enhanced by the use of the spring 46 which urges the braking face 25 into firm engagement with the felt

strip 12. This strip incidentally is preferably employed because of its friction surface, the strip thereby increasing the braking action of the face 25. Accordingly, it will be apparent that the sash cannot lower under its own weight or under the influence of any force directly applied to the sash. If the sash is to be lowered, the operator will turn the crank 53 in a clockwise direction. This exerts a direct downward force on the cable end 51, which force is transmitted vertically to the lower end of the arm 24 and at a slight angle to this arm, and results in a resultant force acting toward the right at the lower end of the arm 24 as viewed in Figure 2, thus tending to move the lower end of this arm toward the right against the tension of the spring 46. This force may, and usually does, actually move the braking face 25 out of engagement with the strip 12. Appreciable movement is unnecessary since the forces transmitted to the lower end of the arm in the manner stated will relieve braking pressures of the surface 25 against the felt 12, and accordingly, the window will be lowered. The force referred to, acting downwardly on the lower end of the arm, not only tends to swing such end of the arm inwardly but also transmits a force through the body of the holding device to the ball 35, thence through stem 37 and spring 38 to the channel 42 to lower the window. Accordingly, it will be apparent that the window readily may be raised either by the application of direct manual force to the window or by rotating the crank 53 in a counterclockwise direction, and the window readily may be lowered by rotating the crank 53 in a clockwise direction to pull downwardly on the cable end 51 to swing the lower end of the arm 24 to the right and apply force therethrough to the window through the ball 35 and associated elements.

The spring 38 cushions raising and lowering forces transmitted to the sash. Additionally, the springs at opposite sides of each sash exert outward forces to maintain the wheels or rollers 32 in firm rolling engagement with the strips 12, thus stabilizing the sash in any position.

Where the raising and lowering means is provided with its own holding means, the body of the holding device, the stem 44, tube 45 and spring 46 may be eliminated, thus leaving only the ball 35 and associated elements. Under such conditions, the cable 60 may be directly connected to the ball as suggested in Figure 6, and movement of the cable 60 by the operating means associated therewith will readily raise and lower the window. Under such conditions, the spring 38 again acts as a movable and deformable cushion means for transmitting forces to the sash.

It will be apparent that each of the holding devices may be made entirely as a self contained unit and readily attached to the window. It merely is necessary to manufacture the window frame at each side of the window with the vertical groove or recess 11, attach the holding device to each edge of the sash and insert it in position. The device is simple in construction and quite rugged, and provides a highly simplified type of holding means whereby a vertically movable sash may be held in any desired vertically adjusted position.

The device shown embodies the invention in a preferred form, but it is intended that the disclosure be illustrative rather than definitive, the invention being defined in the claims.

I claim:

1. A device for holding in vertically adjusted positions a window sash operable in conjunction with a frame having a friction surface parallel to the edge of the sash, comprising a hollow body formed relatively flat and lying substantially in a common plane with the sash, a socket carried by said body adjacent the edge of the sash and spaced laterally from said friction surface, a ball arranged in said socket and having a shank projecting therefrom toward the sash, resilient means connecting said shank to the edge of the sash to fix said body resiliently with respect to the sash, said body having an

arm inclined downwardly away from the edge of the sash and provided adjacent its lower end with a smooth surface engageable flat against said friction surface, said surfaces being spaced laterally from the sash a greater distance than said socket whereby the weight of the sash tends to swing said arm away from the sash to maintain engagement between said surfaces to hold the sash against downward movement.

2. A device according to claim 1 provided with resilient means arranged between said arm and the edge of the sash and urging the lower end of said arm away from the edge of the sash to tend to maintain said surfaces in engagement with each other.

3. A device according to claim 1 provided with a wheel rotatably supported in said body and projecting from the edge thereof opposite the edge of the sash and in engagement with said friction surface, said wheel having its axis substantially above said smooth surface and spaced laterally therefrom away from said friction surface.

4. A device for holding in vertically adjusted positions a window sash operable in conjunction with a frame having a friction surface parallel to the edge of the sash, comprising a body arranged adjacent the edge of the sash, a leaf spring having opposite end portions diverging toward the edge of the window, means for anchoring the center of said leaf spring to said body, a channel fixed to the edge of the sash and provided with vertically spaced lips parallel to the plane of the edge of the sash and beneath which the extremities of said spring are slideable, a roller carried by the side of said body opposite the sash and engageable with said friction surface to roll thereover, said leaf spring urging said body away from the edge of the window to maintain said roller in engagement with said friction surface, said body having a lower arm diverging downwardly

away from the edge of the sash and provided adjacent its lower end with a smooth surface lying flat against said friction surface, said means for anchoring the center of said leaf spring to said body being spaced laterally a substantial distance from said friction surface whereby the weight of the sash tends to maintain said smooth surface against said friction surface to hold said sash against downward movement.

5. A device according to claim 4 provided with an operating cable having one end connected to the top of said body, upper and lower pulleys, said end of said cable extending over said upper pulley, then downwardly around said lower pulley and having its other end extending upwardly, said other end of said cable being connected to the lower end of said arm at a point closer to said friction surface than said means for anchoring the center of said leaf spring to said body whereby a downward pull on said other end of said cable transmits forces to said arm including a resultant force laterally 20 away from said friction surface to tend to release said surfaces from each other.
